SIDE GUARD FOR BEDS

James G. Dyett, North Evans, and Boyd A. Doty, Buffalo, N. Y., assignors to Hard Manufacturing Company, Buffalo, N. Y.

Application May 12, 1954, Serial No. 429,252

2 Claims. (Cl. 5—331)

This invention relates to side guards which may be applied to beds for preventing persons from falling out of the beds at the sides thereof, and which are movable from inoperative lower positions to operative raised positions.

Side guards for beds have commonly been employed but have heretofore been of clumsy, awkward, or unsightly construction, and it is, consequently, one of the objects of this invention to provide a side guard of relatively simple and inexpensive construction comprising a small number of parts and which may be made of an appearance to harmonize with the bed structure. It is also an object of this invention to provide a side guard which can be easily attached to a bed, and which is easy to operate to shift the side guard vertically in and out of operative position. Another object is to provide a side guard of this type with means of improved construction for locking the side guard in and releasing it from its upper position.

Other objects and advantages will be apparent from the following description of one embodiment of the invention and the novel features will be particularly pointed out hereinafter in connection with the appended claims.

In the accompanying drawings:

Fig. 1 is a side elevation of a bed provided with a side guard and mounting therefor embodying this invention and showing the side guard in its raised position.

Fig. 2 is a similar view thereof, showing the side guard in lowered position.

Fig. 3 is a fragmentary sectional elevation thereof, on an enlarged scale, on line 3—3, Fig. 1.

Fig. 4 is a fragmentary longitudinal elevation thereof, partly in section, on line 4—4; Fig. 3.

Figs. 5 and 6 are fragmentary sectional plan views thereof, on lines 5—5 and 6—6 respectively, of Fig. 3.

Fig. 7 is a perspective view of an ear or lug for use in releasably mounting a side guard supporting member on a bed.

Fig. 8 is a perspective view of a socket member secured to a bed in a position to receive the ear or lug shown in Fig. 7.

The bed may be of any usual or suitable construction, being provided with the usual head frame including a pair of upright legs 10 and a foot frame including upright legs 11, and 12 represents the usual side rails which connect the head and foot frames of the bed. The bed may be provided with a spring frame 14 of any usual or suitable construction, that shown being of the adjustable type commonly used in hospitals, but a spring frame of any other type may be employed. The side guard may be of any suitable or desired structure, but as illustrated by way of example, includes a main frame member, preferably of tubular form, having an upper substantially horizontal part 16 terminating in its opposite ends in downwardly extending parts or ends 17. The side guard shown also includes two other longitudinally extending members 18 and 19, preferably also tubular, arranged below the part 16 and in spaced relation to each other and suitably secured to the downwardly extending ends 17 of the side guard. The lower member 19 connects the lower ends of the ends 17 of the side guard.

Our improved structure for mounting the side guard on a bed includes a pair of upright channels or tracks 21

2

which may be formed, for example, of sheets of metal bent into approximately tubular form except that the longitudinal edges do not meet, thus forming longitudinal openings or slots 22. One of these guide channels or tubes for each side guard is mounted on a leg 10 of the head frame of a bed and the other is mounted on a leg 11 of the foot frame, these guide tubes being mounted in such manner that the slots of these two tubes face each other. These guide tubes are removably mounted on the legs of the bed ends to guide the side guard in its up and down movement, the side guard being for that purpose provided with means extending through the slots 22 for movement within the hollow guide tubes when the side guard is moved up and down, and for securely holding the side guard in correct relation to the bed. For example, the tubular member 18 of the side guard is provided at the opposite ends thereof with bushings formed to receive threaded bolts or pins 25, which extend through the slots 22 of the guide tubes with the heads 28 of the bolts arranged within the channels. Rollers 26 are rotatably secured to the bolts within the guide channels or tubes. These rollers may be provided with recesses 27 into which heads 28 of the bolts 25 may extend for preventing disengagement of the bolts with the rollers. The rollers are of considerably larger diameter than the widths of the slots 22, and, consequently, as the side guard is moved up and down, these rollers will move within the guide tube to facilitate the up and down movement of the side guard and also act to prevent the bolts 25 from becoming disengaged from the guide tubes 21.

The lower tube 19 of the side guard is provided at opposite ends thereof with outwardly extending rods or pins 30 which also extend through the slots 22 of the guide tubes and are connected with rollers 31 arranged within the guide tubes 21. These rollers may be of the same shape or construction as the rollers 26 and each rod or pin 30 may also be provided with a disk or washer 32 secured thereto and extending into the hollow portion of the roller, for holding the roller on the pin.

Means are also provided for locking the side guard in its upper position, and this is preferably accomplished by means of the pin 30 in the lower tube 19 of the side guard. In the construction provided for this purpose, the pins 30 are slidably arranged in the ends of the tube 19.

For example, the pins may extend through suitable apertured guide members arranged within the tube 19. These guide members may, for example, be in the form of U-shaped parts 34 having apertures in the legs thereof through which the pin 30 may extend, these guide members for the pin being held in the lower tubular member 19, for example, by means of screws 35. Two of these guide members 34 are arranged in the lower tubular member 19 in spaced relation to each other. Each pin 30 is urged outwardly from the tube 19 by means of a coil spring 36 extending about a part of the pin, this spring abutting at one end thereof against a disk or washer 37 suitably secured to the pin 30 and bearing at its other end against one of the fixed guide members 34 for the pin. Any other means for slidably mounting the pins 30 on the tube 19 may be employed. Each guide tube 21 is provided with a hole in a part thereof through which the end of the pin 30 may extend when the side guard is in its upper position, as clearly shown in Fig. 4. The springs 36 at each end of the tube 19 urge the pins 30 into the holes provided in the guide tubes and each pin is also provided with a finger piece or handle 39 secured to the inner end thereof and extending outwardly through a slot 40 in the lower tube 19 of the side guard. Consequently, when the side guard is raised and reaches its upper position, the outer ends of

the two pins 30 at opposite ends of the tubular member 19 will be urged by the springs 36 to enter the holes in the

guide tubes, and thus hold the side guard in its upper or operative position. When it is desired to lower the side guard, it is merely necessary to engage the two finger pieces or arms 39 and move the same toward each other against the action of the springs 36, thus withdrawing the pins 30 out of the holes in the guide tubes so that the side guard may be lowered.

In order to retain the rollers 26 and 31 in the guide tubes 21, the upper ends of the guide tubes may be closed, as indicated at 42, and thus also form a finished appearance of the upper ends of the guide tubes. The lower ends of the guide tubes are preferably each provided with a bolt 43 extending crosswise of the guide tube through suitable apertures provided therein and engaging with a nut 44. Preferably the bolt also extends through a short tube or sleeve 45 which may be made of rubber or other cushioning material. These resilient sleeves or tubes 45 are contacted by the lower rollers 31 when the side guard is moved into its lowest position, thus greatly reducing any noise which would result from the dropping of the side guard and also avoiding shock or annoyance to a person in the bed. The bolt also reinforces the lower end of the guide tube 21 and prevents widening of the slot 22. Any other means for closing the lower end of the guide tube and providing shock absorbing means for the side guard may be employed.

The guides 21 may be secured to the legs 10 and 11 of the head and foot frames of a bed in any suitable or desired manner. In the construction shown, an ear or lug 48 is provided, one of which is welded or otherwise secured to each guide tube 21 and which has a downwardly projecting tongue 49 formed thereon for cooperation with socket members 50 which may be secured to the legs of the head and foot frames of the bed in any suitable manner. In the construction shown by way of example, the socket members 50 are mounted on U-shaped parts 51 which may be welded or otherwise secured to the legs of the head and foot frames of the bed. These socket members and their securing parts 51 are relatively small and inconspicuous and consequently, are not objectionable when permanently secured to a bed, particularly since they are arranged below the spring frame of a bed where they are practically out of sight, as clearly shown in Figs. 1 and 2.

The upper portion of each guide tube 21 is releasably clamped or hooked to portions of the legs of the head and foot frames of the bed in any suitable manner. The clamping means shown by way of example, see particularly Fig. 5, include channel-shaped brackets 55, one of which is secured to each guide tube with its legs extending horizontally outwardly. The outer ends of the legs are welded to a transverse plate or hinge member 56 provided with ears 57 at opposite ends thereof to which two hook or clamping members 58 and 59 are hinged. These hook members are each formed to extend about opposite sides of the leg of the bed and to extend partly about a third side and are provided with outwardly extending substantially parallel ends 60, which are connected by a bolt 61, which extends through suitable slots in these two extensions 60 and is engaged by a thumb nut 62 for securely urging the two hinged members toward each other. It is, of course, not necessary to press the two hinged hook members against the legs of the end frames, and consequently, stops 63 and 64 are provided to limit the extent to which the bolt 61 may swing the hinged hook members toward each other. Suitable pads 65 are arranged on the inner faces of the two hook members 58 and 59 and on the hinge member 56 in position to engage the sides of a leg of the bed so as to avoid rattling and marring the legs 10 and 11. Any other means for securing the guide tubes 21 to the bed ends may, of course, be provided, if desired.

In applying the side guard to a bed, the ears or lugs 49 of the two projecting tongues 48 of the guide tubes are first inserted into the socket members 50 and the

hinged hook members 58 and 59 are then swung from the broken line position as shown in Fig. 5, into the full line positions and securely connected by means of the bolt 61. The guide tubes will then be securely held

5 in place on the bed. When it is desired to release the side guard from the bed, the hook members 58 and 59 are first released and swung into the broken line positions in Fig. 5, whereupon the two guide tubes 21 may be raised to disengage the tongues 49 from the sockets 30.

10 While only one side guard is described herein, it will be obvious that in most cases two side guards are employed, both of which may be identical. When the side guards are removed from a bed, only the socket members 15 49 and their fastening devices 50 will remain in place on the bed and this socket member, of course, may also, if desired, be removably mounted on a leg of a bed. The side guards include relatively few parts and are, therefore, comparatively easy to construct.

20 It will be understood that various changes in the details, materials, and arrangements of parts which have been herein described and illustrated in order to explain the nature of the invention, may be made by those skilled in the art within the principle and scope of the invention, as expressed in the appended claims.

We claim as our invention:

30 1. A side guard structure for a bed having end frames provided with upright legs, comprising a side guard, a pair of upright guide tubes provided with slots extending lengthwise thereof and facing said side guard, parts on said side guard extending through said slots and into said tubes for guiding said guard in its up and down movement, and means for connecting said guide tubes to said legs, said connecting means including a socket 35 mounted on each leg and extending outwardly therefrom, a tongue on each guide tube formed to extend into said socket, a pair of hook members pivoted on each guide tube to swing in opposite directions into engagement with said legs, and means for releasably holding 40 said hook members against swinging out of engagement with said legs, said hook members being spaced at a considerable distance from said tongue to hold said guide tubes in fixed positions spaced outwardly from said legs.

2. A side guard structure for a bed having end frames, 45 comprising a side guard including a pair of longitudinally extending tubular members, a pair of upright guide tubes having slots extending lengthwise of said tubes, cooperating parts on said guide tubes and said end frames for supporting said guide tubes outwardly from said end frames with said slots facing said side guard, pins extending beyond the opposite ends of said tubular members of said side guard and through said slots of said guide tubes, rollers within said guide tubes rotatably mounted on said pins and guiding said side guards for up and down movement relatively to said bed, said guide tubes each having a hole in the wall thereof opposite said slot, said pins of one of said tubular members being movable lengthwise of said side guard for passing through said holes, to hold said side guard in its upper position, yielding means within said tubular member for urging said pins outwardly with reference to said side guard into engagement with said holes in said guide tube, and finger pieces extending through a side of said tubular member for withdrawing said pins from said holes.
